CLAIM

We claim the ornamental design for a clothing care machine, as shown and described.

DESCRIPTION

FIG. 1 is a front perspective view of a clothing care machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof;

FIG. 9 is an enlarged right-side cross-sectional view of the encircled portion in FIG. 5 taken through line 9-9 of FIG. 2; and,

FIG. 10 is an enlarged view of the encircled portion in FIG. 8.

The dash-dash broken lines in the figures depict portions of the clothing care machine which form no part of the claimed design.

The dot-dot-dash broken lines encircling portions of the claimed design that are illustrated in enlargements form no part of the claimed design.
